AERIAL TOY

Claude R. Butcher, Oswego, Oreg.

Application October 29, 1943, Serial No. 508,155

3 Claims. (Cl. 46—75)

This invention relates to an aerial toy of the contractible type to be shot into the air whereupon the parts assume their normal position and the toy descends in flight. More particularly the invention is a helicopter toy, is initially propelled upward in collapsed condition and descends in its normal relation of parts.

It is an important object of this invention to provide a collapsible aerial toy that may be handled rather violently in shooting it into the air without fear of disrupting the general relation of parts or impeding its subsequent descent to the ground.

It is another object of this invention to provide, in a toy of the type described, helicopter blades that may be collapsed and nested into a streamlined bundle with the fuselage of the toy and which will readily assume their normal operating position with rapidity upon loss of forward movement following its air projection.

Still another object of this invention is the provision, in a toy of the type mentioned, of novel collapsible support means for a helicopter rotor which means can be easily formed of minimum parts and yet in a manner to afford the maximum of strength and operability.

The foregoing objects and others ancillary thereto I prefer to accomplish as follows:

According to a preferred embodiment of my invention, I support above a simulated airplane fuselage a helicopter rotor. The fuselage has landing wheels, body portion and torque restricting tail surface. Above the fuselage upon a swingable column I mount the rotor. The column swings from the upright or erect position down to alignment with the fuselage. Elastic means is employed to erect the column and tend to keep it in the upright position. Counterweight means are employed to vary the center of gravity to affect as desired the flight characteristics of the toy. Upon the upper end of the column is pivotally mounted a rotor spool from which extend in radial manner the blades of the rotor which are hinged to the spool for nesting purposes. Elastic means is also employed to tend to keep the blades in normal radial or extended position above the fuselage. A hook is provided upon the column for engagement with an elastic propulsion means used in shooting the toy in its collapsed condition into the air. All of the parts are formed of light weight materials having high strength characteristics to insure long and durable life in the toy.

The novel features that I consider character-

istic of my invention are set forth with particularity in the appended claims. The invention itself, however, both as to its organization of parts and its mode of operation, together with additional objects and advantages thereof, will best be understood from the following description of a specific embodiment when read in connection with the accompanying drawing in which

Figure 1 is a side view of my aerial toy.

Figure 2 is a plan view of the toy.

Figure 3 is a side view of the toy as it appears collapsed and about to be placed in flight in the air.

Figure 4 is an enlarged detail of the manner in which the rotor blades are hinged to their supporting spool.

Figure 5 is fragmentary enlarged detail of the manner of supporting the rotor blades from the spool.

Figure 6 is an enlarged fragmentary detail of the rotor support column, and

Figure 7 is a sectional view taken on lines 7—7 of Figure 6.

An aerial toy to serve the purposes of utility must have at least two totally distinct characteristics; it must be capable of absorbing a terrific amount of punishment at the hands of youthful aeronauts; and it must also be capable of accurate and sustained flight including projection to great heights. Accordingly, a preferred embodiment of my invention, referring to the drawing, is constituted by a fuselage body 10 having a torque resisting tail surface 12 secured to one end. As here shown the tail 12 is circular and in effect constitutes a landing runner as well as providing a maximum of surface to the air to resist twisting of the toy as it descends in flight. The thinned forward portion 14 of the body is roughly a quadrant segment and has a pivot pin 16 therethrough on which is mounted the mast column or post 18 to swing from the solid position shown throughout the drawing to the dotted line position suggested in Figure 6. The thicker portions of the body at either end of the quarter segment are stops limiting movement of the mast in either position. An elastic band 20 engaged in notch 22 of the body extends to notch 24 in the post and tends to urge the latter member in the upright position. Wire legs 26, 26 are joined to the post 18 to swing therewith and when in the erect position constitute supports for the wheels 28, 28.

A pin 30 rises from the upper end of post 18 and in its upper extremity is formed to provide

a tow hook 32 which receives an elastic loop 34 upon the launching stick 36 provided for propelling the device under certain conditions.

The spool at hub 38 is rotatable on pin 30 has extending from its under edges the hinged leaves 40 to each of which a rotor blade 42 is attached. The pivots of the hinges are normal to the mast. Between a ring 44 and hooks 46, one of which is provided on each blade, I stretch elastic bands 48 which serve to suspend the blades in the manner shown in Figures 1 and 5.

In that end of the body opposite the tail surface 12 I mount a weight beam 50 on which is mounted the weight 52 for movement along the beam. In this instance the weight is threaded upon the beam to provide gradual adjusting means between the two elements and to retain to a degree the parts in adjusted position.

To collapse the toy preparatory for projection into the air, the post or mast 18 is swung forward into alignment with the body 10. The rotor which is carried thereby is then collapsed against theurgence of the elastic bands 48 into the form shown in Figure 3 where it is retained to the tail surface by a person grasping the parts between his thumb and forefinger. The band 34 is looped around hook 32 and then stretched by pull exerted upon stick 36 in the other hand. When the tail is released the toy will shoot forward into the air in this streamlined condition for many feet. As its forward speed decreases and the slip-stream effect upon the blades recedes the toy tends to come to rest in the air at which time the rotors expand as normal and the post 18 is erected by the action of elastic member 20.

When the device is air borne the rotor which is pitched in the manner of an air screw, begins to turn in simulation of a helicopter and supports the plane to a certain extent against the effect of gravity. Placement of the weight 52 relative the center of gravity will effect the balance of the body 10 upon the rotor so that, when the weight is placed forwardly of the center of gravity the body nose 14 will be tipped forward and the toy will descend gradually and glide forward at the same time. At such times as the center of gravity is shifted more to the rear of the foregoing arrangement the toy will tend to hover over one spot and only descend in a vertical line. Skill may be exercised in the use of the toy to vary these characteristics at will and various forms of flight may thus be obtained. Any tendency in the body to twist upon turning

of the rotor is restrained by the rather large torque resisting tail surface 12 which, in forward flight also serves as a rudder to guide the toy in a fairly straight course.

Having thus described my invention, I claim:

1. In an aerial toy, a fuselage, a saddle having its legs pivoted to said fuselage, a tow hook fastened to said saddle away from the pivot thereof, and folding wings carried by said saddle whereby the same may be swung so that said wings may be folded along said fuselage during towing of said toy, whereby pressure on said hook will retain the saddle in the swung position.

2. In an aerial toy, a fuselage having a mast pivoted thereto to swing to the forward end in a substantially horizontal manner, a tow hook secured to said mast at its apex, a hub rotatable about the axis of the mast and having three equally spaced blades hingedly secured thereto by pivots lying in a plane normal to said mast, elastic means extending between the upper portion of said hub and said blades to urge the same upwardly against said hub which limits the upward motion of said blades, stops limiting movement of said mast from an upright position to a forward horizontal position, resilient means for urging said mast to the upright position, whereby the mast may swing forward and one blade folded under the fuselage and the other two wings will lie one on each side of said fuselage in a streamlined manner, and a torque restraining member on said fuselage.

3. An aerial toy, comprising: a fuselage having a tail rudder and a forward quadrant segmental portion, stops at either end of said segmental portion, a split mast pivoted astride said fuselage adjacent the center of said segmental portion and limited in its swinging movement by said stops, resilient means between an upper portion of said mast and a rear portion of the fuselage, a hub rotatably mounted on said mast at its upper end and having blades forming a rotor hingedly secured to the underside thereof, resilient means between an upper intermediate portion of each blade and an upper portion of said hub to tend to urge the blades into radial extended position with relation to the hub, and a tow hook on said mast for engagement with towing means when the mast is swung to its forward position and the blades are caused to lie in streamlined position alongside the fuselage whereby the toy may be forcefully projected into the air.

CLAUDE R. BUTCHER.
